HUMMING BIRD FEEDER

Harry M. Brown, Jr., 3110 SE. Rex St.,
Portland, Oreg. 97202

Filed June 18, 1968, Ser. No. 12,414

Term of patent 14 years

Int. Cl. D30—02

U.S. Cl. D30—14

FIG. 2

FIG. 1

FIG. 3

FIG. 1 is a front view of a humming bird feeder in accordance with my new design;

FIG. 2 is a top view thereof; and

FIG. 3 is a bottom view thereof.

The broken line segment of a hanging hook is depicted for illustrative purposes only.

I claim:

The ornamental design for a humming bird feeder, as shown and described.
